UNITED STATES PATENT OFFICE.

MICHAEL F. SCHOENBERGER, OF LOS ANGELES, CALIFORNIA.

JOURNAL-BOX EVENER.

1,189,495.

Specification of Letters Patent. Patented July 4, 1916.

Application filed December 15, 1915. Serial No. 67,056.

To all whom it may concern:

Be it known that I, MICHAEL F. SCHOENBERGER, a citizen of the United States, residing at Los Angeles, in the county of 5 Los Angeles and State of California, have invented a new and useful Journal-Box Evener, of which the following is a specification.

This invention relates to railway trucks 10 and more particularly to trucks of the six-wheel type.

It is a well-known fact that the force exerted by the brakes on the truck wheels tends to crowd the journal boxes against 15 the oppositely-arranged guides of their respective pedestals and this continued thrust unless counteracted causes tipping or twisting of the boxes and resultant wear upon their guides. This brake thrust at the end 20 boxes is counteracted by the equalizer bars, the overhanging ends of which are afforded sufficient bearing surface upon the respective box tops to maintain said boxes in true alinement as they move up and down in 25 their guides. At the intermediate box, however, the top bearing surface is utilized to support the abutting ends of both equalizer bars which arrangement diminishes the bearing surface for each abutting end upon 30 the box-top with the result that a comparatively small resistance is offered to the aforesaid torsional stress attending the brake action and accordingly this brake thrust heretofore has tipped the intermediate box 35 and caused it to gradually wear away the oppositely-arranged guide face, which wear in time produces looseness and necessitates replacing of both the box and pedestal.

An object of this invention is to avoid 40 the aforesaid tippage and resultant wear by providing means which may be applied to truck constructions of standard type whereby an intermediate box is maintained in true alinement as it moves up and down in 45 its pedestal, producing a box that is as free from any tendency to tip as are each of the end boxes.

In carrying out this invention I provide 50 an evener plate to rest upon the top of each intermediate box of the truck, said plate having extensional supporting means in the form of lugs at each side thereof, the ends of which lugs extend beyond the box when the same is in position. The abutting ends 55 of the equalizer bars are provided with side shoulders adapted to seat on said lugs

throughout their length, which arrangement affords a bearing, the length of which is of such extent as to provide sufficient leverage to thereby gain stability against any thrust 60 in the longitudinal plane of the equalizer bars.

Another object is to provide means of this character that may be applied to standard truck constructions as an attachment and in 65 which durability, long life and superior efficiency of operation are gained.

Further objects are cheapness, simplicity and strength of construction as well as compactness in arrangement.

Other objects and advantages may appear as the invention is unfolded in the detailed subjoined description.

The accompanying drawings illustrate the invention.

Figure 1 is a side elevation illustrating the invention as applied to a six-wheel railway truck. Fig. 2 is an enlarged fragmental elevation, partly in section on line α^2 , Figs. 3 and 4, and illustrating the application of the invention to an intermediate journal-box. Fig. 3 is a sectional end elevation viewed from line α^3 , Fig. 2. Fig. 4 is a fragmental plan, partly in section and viewed from line α^4 , Figs. 2 and 3, showing parts in assembled position. Fig. 5 is a fragmental enlarged cross-sectional view on line α^5 , Fig. 2. Fig. 6 is a perspective view illustrating an abutting end of one of the equalizer bars with which the invention is 30 applied. Fig. 7 is a bottom perspective view of the evener plate detached. Fig. 8 is a top perspective view of the evener plate 35 detached.

Arrows on the various section lines indicate the direction of sight.

The six-wheel type of truck shown in the drawings is of usual construction, having wheels 1 secured to axles 2 that are journaled in boxes 3, said journal boxes being 100 mounted in the customary alined pedestals 4 depending from the side sills 5 of the truck.

The truck side-frames are of the equalizing bar type consisting of an adjacent pair of equalizer bars 7, the abutting ends 8 of 105 which are carried by the intermediate box 3 while the opposite ends 9 are carried by the end boxes 3'. The usual springs a , are interposed between the sill 5 and the intermediate portions of the adjacent equalizer 110 bars 7 at each side of the truck, supporting the truck sills in the usual way from the

journal boxes, through the equalizer bars, so that the sill frame is capable of the proper vertical movement in respect to the truck wheels.

5 The pedestals or journal box guides are all of similar construction and each is secured to its sill 5 in the ordinary manner by bolts 10, said pedestals being provided with oppositely-arranged guides 11, 12, and side 10 openings 13 through which openings the ends of the equalizer bars extend to seat upon their respective boxes. Said boxes are in duplicate, one of the other, so that any one thereof may be applied to any one 15 of the several pedestals and each box has the usual inner bearing brass 14 and vertical guide-ways 15, which guide-ways fit the guides 11, 12. The parallel ribs 16 upon the box top form an equalizer bar seat at the 20 end boxes 3', see Fig. 1, and a semi-circular mid-ridge 16' extends across between said ribs 16 and engages the usual equalizer bar seat 17, the ribs 16 and the ridge 16', however, being utilized somewhat differently for 25 the intermediate box as will hereinafter appear.

All of the foregoing structure is of a standard type used in six-wheel truck construction including the complementary 30 quadrant grooves 18 at the lower corners of the abutting ends 8, the positioning of which in the present instance will appear later.

The brakes 19, shown mounted diagrammatically in Fig. 1, are operated by suitable means, not shown, the construction and operation of which are well known in the art.

The abutting ends 8 of the equalizer bars that meet in the vertical mid-plane of the 40 intermediate axle 2 have heretofore rested upon the top of the intermediate box in which instance said intermediate box affords approximately one-half as much bearing surface for the equalizer bars as at the 45 end boxes to resist the torsional stress of the brake upon application of the same. This brake thrust tends to crowd the box against the thrust-receiving pedestal guides 12, in time causing tippage of the box and wearing 50 away of the guide faces and to overcome this difficulty I provide an evener plate 20 resting upon the top of the intermediate box to support the abutting ends 8 of the adjacent side equalizer bars, said plate being provided 55 with supporting means extending beyond the side boundaries of the box in the plane of the equalizer bars, which extensional supporting means serves to counteract this brake thrust and produce as stable 60 a condition at the intermediate box as at the end boxes. Said means in the present instance comprises side lugs 21 extending at right angles from a bottom plate 22 and overhanging beyond said plate at the ends 65 thereof, being preferably aslant upwardly

and outwardly at *c* from the plate body to form top ledges or faces 23, the length of which is thus made approximately twice the length of the plate. The width of the plate corresponds to the width of the equalizer bar seat formed between the box ribs 16, and the plate 22 is provided with a bottom recess 24 extending transversely of the supporting lugs 21, the arrangement being such that the evener plate may seat between the ribs 16 of the intermediate box with the recess 24 over the transverse mid-ridge 16' thus to hold the evener plate in place upon the box top.

The abutting ends 8 which heretofore have rested directly upon the intermediate box top between the ribs 16 are now trimmed down to form side shoulders 25 that are adapted to seat on the supporting lugs 21, the narrowed lower portions 26 of each abutting bar end fitting between said lugs with the bottom surface *d* bearing upon the top surface *c* of the plate 22, which bearing surfaces together with the supporting lugs 21 and shoulders 25, form a combined bearing surface to support the abutting ends 8. A plate ridge 27 similar to the ridge 16' accommodates the quadrant grooves 18 that heretofore have seated directly upon the mid-ridge 16' of the box. 95

It is thus seen that in order to gain greater stability than has heretofore been possible for the intermediate journal boxes of a truck I have provided an extensional support affording a comparatively greater length 100 through which the overhanging ends of the equalizer bars act, thus attaining a more extensive leverage to maintain the box in true alignment and thereby avoid tippage of the box by the brake thrust and consequent 105 wearing away of the opposite guides 12; while in the case of the abutting bars resting directly upon the top of the box, said box is rendered much less stable due to the decreased leverage through which the ends 110 of the equalizer bars act and the resultant wear is consequently made very detrimental to the durability and long life of the device.

For the purpose of preventing any spreading of the upright side lugs 21 or breaking away of the top faces 23 thereof due to the weight of the load carried by them, said faces are each arranged aslant downwardly and outwardly, and the lower faces of the 120 complementary shoulders 25 seating upon the faces 23 are correspondingly beveled at 28, which arrangement produces a tendency to crowd the lugs together when the shoulders are in place thereon. 125

The invention may be readily applied as an attachment to present truck constructions by merely dismantling the equalizer bars, inserting the evener plate in place upon the intermediate box top and, after narrow- 130

ing said bars down to form the shoulders 25, the same may be seated upon the supporting lugs 21 with the narrowed portion 26 positioned therebetween and bearing upon the bottom plate 22.

5 I claim:

1. The combination with a journal box guide, a journal box in said guide and truck equalizer bars carried by the journal box, of 10 a plate upon the top of said box and provided with an extensional supporting surface to co-act with said equalizer bars to support the same and thus gain stability against tipping of the box.

15 2. The combination with a journal box guide, a journal box in said guide and truck equalizer bars carried by the journal box, of an evener plate upon the top of said box and supporting the equalizer bars, said plate 20 extending beyond the side boundaries of the box and in the plane of said equalizer bars to afford sufficient leverage to thus maintain the box in alinement in its guide.

25 3. The combination with a journal box guide, a journal box in said guide and truck equalizer bars carried by the journal box, of an evener plate upon the top of said box, supporting means on said plate extending beyond the side boundaries of the box and 30 in the plane of said equalizer bars, said equalizer bars being adapted to seat upon said supporting means to afford sufficient leverage to thereby gain stability.

35 4. The combination with a journal-box guide, a journal box in said guide and truck equalizer bars carried by the journal box, of an evener plate upon the top of said box,

a supporting lug at each side of said plate, the equalizer bars being positioned between said lugs and bearing on the plate, shoulders on the equalizer bars and adapted to seat upon said lugs, said shoulders and lugs extending beyond the side boundaries of the box to afford sufficient leverage to thus maintain the box in alinement with its 40 45 guide.

5. The combination with a journal-box guide, a journal box in said guide and abutting truck equalizer bars carried by the journal box, of an evener plate upon the top of said box, side supporting lugs on 50 said plate and extending beyond the box in the plane of said equalizer bars, the top face of each lug being aslant downwardly and outwardly, and side shoulders on the equalizer bars, the bottom faces of said shoulders being beveled to correspond with and seat upon the top faces of said lugs.

6. A journal box evener comprising a bottom plate, side lugs on said plate, said lugs 60 overhanging beyond the plate at each end thereof to form extensional supporting ledges for the purpose set forth.

7. A journal box evener comprising a bottom plate, extensional means on said plate, 65 said means overhanging beyond the plate at each end thereof to form supporting ledges for the purpose set forth.

In testimony whereof, I have hereunto set my hand at Los Angeles, California, 70 this 8th day of December, 1915.

MICHAEL F. SCHOENBERGER.
